UNITED STATES PATENT OFFICE.

EDWARD THOMAS, OF EAST CHICAGO, INDIANA.

AUTOMOBILE ALARM SIGNAL.

Application filed September 23, 1918. Serial No. 255,311.

To all whom it may concern:

Be it known that I, EDWARD THOMAS, a citizen of the United States, and a resident of the city of East Chicago, in the county of 5 Lake and State of Indiana, have invented certain new and useful Improvements in Automobile Alarm Signals, of which the following is a specification.

My invention relates to improvements in 10 automobile alarm signals, and has for its object the provision of an improved construction of this character adapted to prevent the stealing or unauthorized moving of automobiles or the like.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1, is a longitudinal view of an apparatus embodying the invention and shown as 25 mounted on the drive shaft of an ordinary automobile,

Fig. 2, an enlarged section taken on line 2—2 of Fig. 1,

Fig. 3, an enlarged partial longitudinal 30 section through the apparatus,

Fig. 4, a section taken on line 4—4 of Fig. 3,

Fig. 5, a section taken on line 5—5 of Fig. 3,

35 Fig. 6, a detail view of an actuating member employed in the construction, and

Fig. 7, a detail view of a clutch member employed in the construction.

The preferred form of construction, as 40 illustrated in the drawings, comprises a suitable casing 8 mounted on the automobile, enclosing a portion of the drive shaft 9 thereof. Alarm signal bells 8' are mounted on opposite sides of casing 8, as shown, 45 and operating hammers 10 are pivoted at 11 to the sides of casing 8 in operative relation with said bells, actuating springs 10' being connected with said hammers to actuate same. Each of the hammers 10 is in substantially 50 U-form and is provided on its outer end with a hammer head 12, arranged to strike the corresponding bell 8', and the other side of each hammer passes through a suitable slot 13 in the rear wall of the casing 8 and 55 is equipped with a lug or ear 14 adapted to

engage radiating pins 15 on an actuating disc 16 loosely mounted on drive shaft 9. The actuating disc 16 is provided in its rear face with a clutch recess 17 adapted to receive a clutch tooth 18 on the forward face 60 of a clutch member 19 fixed on shaft 9. Actuating member 16 is provided on its forward side with a hub 20 having a groove 21 therein adapted to receive a fork 22 carried by a reciprocating actuating rod 23 operating through a suitable guide opening in the forward side of casing 8 and operatively connected with a rack bar 24. A compression spring 25 is imprisoned between the fork 22 and the forward wall of casing 8 and 65 serves to normally hold the clutch members 16 and 19 in engagement. Rack bar 24 meshes with the pinion 24' on a vertical shaft 26 extending upwardly under the edge of the driver's seat of the automobile. 70 At its upper end shaft 26 carries a spring-held operating arm 27 adapted to engage a lug or finger 28 on the under side of the operator's seat 29, and whereby said shaft may be locked in position to hold the clutch members 17—18 out of engagement. 75

In use, when the driver leaves his car, he releases the shaft 26, permitting of engagement between clutch members 17—18 and consequent actuation of the alarm bells upon 80 movement of the drive shaft of the automobile. This effectually prevents unauthorized or surreptitious removal of the car, inasmuch as movement of the same gives an alarm signal that would attract the attention of the driver or of passers by, thus frustrating the attempt. When the driver desires to operate the car normally, he simply actuates the shaft 26 to disengage the clutch members 17—18 and locks the same in withdrawn position by engaging arm 27 behind finger 28, whereupon the automobile may be operated in the usual manner without giving an alarm signal. 90

While I have illustrated and described the 100 preferred form of construction for carrying my invention into effect, this is capable of variation and modification without departing from the spirit of the invention. I, therefore, do not wish to be limited to the 105 precise details of construction set forth, but desire to avail myself of such variations and modifications as come within the scope of the appended claims.

Having described my invention, what I 110

claim as new and desire to secure by Letters Patent is:—

1. The combination with a shaft of an automobile, of an audible signal in operative relation therewith; spring actuated means for placing said shaft in operative connection with said signal; manually operable means for disconnecting said signal from said shaft; and locking means for locking 10 said parts in inoperative position, substantially as described.
2. The combination with a shaft of an automobile, of a signal bell in operative relation therewith; a spring-actuated hammer 15 arranged to sound said bell; an actuating and a clutch member mounted on said shaft, one of said members being fixed to said shaft and the other loose thereon; a spring normally holding said actuating and clutch 20 members in operative engagement with each other; manually operable means for separating said members; and a lock for locking said members in separated condition, substantially as described.
3. The combination with a shaft of an automobile, of a signal bell in operative relation therewith; a spring-actuated hammer arranged to sound said bell; an actuating and a clutch member mounted on said shaft, 30 one of said members being fixed to said shaft and the other loose thereon; a spring normally holding said clutch and actuating members in operative engagement with each other; an actuating rod arranged to separate 35 said members; a rack bar on said rod; a pinion meshing with said rack bar; an actuating shaft fixed to said pinion and arranged in operative relation with the automobile driver's seat; and means for locking 40 said shaft in position to hold said actuating and clutch members separated, substantially as described.
4. The combination with the drive shaft 45 of an automobile, of a casing enclosing a portion of said shaft; signal bells on opposite sides of said casing; spring actuating hammers pivoted on said casing and adapted to sound said bells; an actuating member loose on said shaft and provided with radi-

ating pins adapted to strike said hammers to sound said bells; a clutch fixed to said shaft and arranged to engage said actuating member upon longitudinal movement of the latter on said shaft; a fork engaging said actuating member to effect longitudinal movements thereof on said shaft and permit rotations thereof; a reciprocating actuating rod connected with said fork; a spring imprisoned between said fork and a wall of said casing and arranged to normally press said actuating member into engagement with said clutch; a rack bar operatively connected with said actuating rod; a pinion meshing with said rack bar; an actuating shaft fixed to said pinion and arranged in operative relation with the automobile driver's seat; and means for locking said shaft in position to withhold said actuating member from engagement with said clutch, substantially as described.

5. The combination with a vehicle having a part moving with each movement of the vehicle, of a mechanically operated alarm mounted upon the vehicle, and provided with movable parts engaging with the moving parts of the vehicle and actuating said alarm on movement of said vehicle, irrespective of direction, and private means for rendering said alarm inoperative.

6. The combination with a vehicle having a part moving with each movement of the vehicle, of a mechanically operated alarm, and means for operating said alarm comprising, a rotatable member, means for driving said rotatable member from said moving part, means for operating said mechanical alarm irrespective of the direction of rotation driven by said rotatable member, and means for moving said rotatable member into and out of engagement with said driving means and private means for rendering said alarm inoperative.

In testimony whereof I have signed my name to this specification in the presence of two subscribing witnesses.

EDWARD THOMAS.

JOSHUA R. H. POTTS,
HELEN F. LILLIS.
